UNITED STATES PATENT OFFICE.

HENRY S. GRACE, OF SAN FRANCISCO, CALIFORNIA, ASSIGNOR TO J. J. McDONALD, OF SAN FRANCISCO, CALIFORNIA.

TRAMMEL POINT.

1,427,376.

Specification of Letters Patent. Patented Aug. 29, 1922.

Application filed November 17, 1920. Serial No. 424,651.

To all whom it may concern:

Be it known that I, HENRY S. GRACE, a citizen of the United States, residing at San Francisco, in the county of San Francisco and State of California, have invented new and useful Improvements in Trammel Points, of which the following is a specification.

This invention relates to improvements in trammel points or beam compasses. The object of the invention is to provide a beam compass which will be easier to operate than those heretofore used and which will be graduated either to sixty-fourths of an inch 15 or on the metric system to one-thousandths of an inch.

In the accompanying drawing, Figure 1 is a broken front elevation of my improved beam compass; Figure 2 is a similar view 20 of the operative end thereof on an enlarged scale; Figure 3 is a plan view of a portion thereof; Figure 4 is a side view of the portion shown in Figure 3 looking from the side opposite from Figure 2.

Referring to the drawings, 1 indicates the beam of my improved beam compass, a portion only being here shown. Near one end of said beam is clamped thereto a U-shaped holder 2. Through holes 3 in one side thereof of slide guide pins 4, the inner ends of which are attached to a spring clamp sheet 6 which is clamped against the beam 1 between the flanges 7 and 8 thereof by a screw 9 screwed through the side of the U-shaped holder 35 through which the pins 4 extend and the inner end of which bears against the clamp sheet 6. By turning said screw by means of the handle 10, the clamp sheet 6 may be clamped firmly against a side of the beam 40 between the flanges 7 and 8 and thus firmly secure the U-shaped holder in position. Upon the outer side of the middle portion of said holder is pivoted, as shown at 11, a compass leg 12 having adjustably secured 45 therein a needle 13, and for the purpose of turning said leg upon its pivot 11, said leg is provided with an arm 14 extending at right angles thereto and forked at its free outer end, as shown at 15 to extend on opposite sides of a screw 16 fixedly attached to the middle side of the U-shaped clamp holder, a nut 17 being provided to turn upon said screw, and outside of said arm, and thus move said arm inwardly. The free end of 55 a spring 18 bears against the inner side of

said arm and moves it outwardly, said arm being secured at said end as shown at 19 to the U-shaped holder 2. By turning said nut, the position of the leg may be varied as desired, although in general no change will be made in the position of this point, as the difference in the positions of the compass will be made in the other member thereof, which I am about to describe. 22 indicates a U-shaped holder, similar in general construction to the U-shaped holder 2, from one member of which at one end thereof extends a post 23 carrying a bearing 26, through which can slide a short bar 25, square in cross section to fit snugly in the square inner cavity of the bearing 26. The outer end of said bar 25 is split, and the two outer ends of the split parts are connected by a screw 20 so that said outer ends can be drawn closely together by said screw, and clamp there- 75 between a stem 27 of a compass member 28, here shown as an inking member, although, when desired, it can be removed and substituted by the stem of a pencil carrying member.

Said square bar 25 is extended in the opposite direction to the ink carrying member in the form of a long screw 29 which extends through a bearing 30 supported by a support 31 extending from the other end of said U-shaped holder 22, a coiled spring 32 surrounding said screw and bearing at its rear end against said bearing 30 and at its front end against a washer 34 surrounding said screw and abutting against the rear end 90 of the square portion of said bar 25. Said helical spring thus constantly presses the square bar and the inking member carried thereby towards the leg 12. A cylinder 33 is graduated as shown at 35, and a mark 36 95 is carried on the bearing 30 to which mark one of said graduations 35 is brought into alinement. A wheel 37 surrounds the threaded extension 29 of the bar 25 for convenience in manipulation. It is obvious that 100 by turning said wheel through the space between two adjacent graduations 35, the marking member 28 will be advanced towards the stationary member 12 by means of the spring 18. Said square hollow bar is 105 graduated on one side every one-thirty-second of an inch and on the opposite side every one-sixteenth of an inch, and on the outer side every one-sixty-fourth of an inch, so that by observing how far said bar projects 110

beyond said bearing, the distance of the marking point from the stationary point can be estimated in sixty-fourths of an inch, thirty-seconds of an inch, one-sixteenths of 5 an inch, as may be desired.

If one revolution of the cylinder 33 corresponds to an advance of the bar 25 through a distance equal to one thread of the screw and there are twenty five graduations in the 10 cylinder and if there are forty threads of the screw to the inch, then each of the graduations of the cylinder would correspond to one-one-thousandths of an inch.

I claim:

15 1. In a beam compass, the combination of a beam, a stationary point carried thereby, a movable point, and means for regulating the distance of the second point from the first point, which means comprises a holder 20 slidable upon the beam, bearings carried by the holder, a bar movable longitudinally in the bearings and having one end portion thereof formed angular in cross section, one of said bearings being of angular form to receive the angular 25 portion so as to prevent turning of said bar, said bar being provided with screw threads at its other end portion, an adjusting nut turned on the screw threaded portion of the bar, means for 30 preventing longitudinal movement of the nut, said bar where angular being graduated on one face, every one-thirtieth of an inch, on another face every one-sixteenth of an inch, on another face every one-sixteenth of

an inch, and on another face, one-sixty-fourth of an inch, said screw threaded portion having forty screw threads to the inch and a cylindrical portion on the nut on which there are twenty-five graduations. 35

2. In a beam compass, the combination of a beam, a stationary point, a movable point, 40 means for regulating the distance of the second point from the first point by either ordinary fractions of an inch or by thousandths of an inch, as desired, which means comprises a holder slidable upon the 45 beam, bearings carried by the holder, a bar movable longitudinally in the bearings and having one end portion thereof formed angular in cross section, one of said bearings being of angular form to receive the angular 50 portion so as to prevent turning of said bar, said bar being provided with screw threads at its other end portion, an adjusting nut turned on the screw threaded portion of the bar, means for preventing longitudinal 55 movement of the nut, said bar where angular, being graduated on one face, every one-thirtieth of an inch, on another face every one-sixteenth of an inch, and on another face, one-sixty-fourth of an inch, said 60 screw threaded portion having forty screw threads to the inch, a cylindrical portion on the nut on which there are twenty-five graduations and a spring against the action of which said bar is moved.

HENRY S. GRACE.
